US0D1033520S

(12) **United States Design Patent** (10) **Patent No.:** **US D1,033,520 S**
(45) **Date of Patent:** **** Jul. 2, 2024**

(54) **CAMERA HOUSING**

- (71) Applicant: **GoPro, Inc.**, San Mateo, CA (US)
(72) Inventors: **Scott Alberstein**, San Francisco, CA (US); **Daniel J. Coster**, Oakura (NZ)
(73) Assignee: **GoPro, Inc.**, San Mateo, CA (US)
(**) Term: **15 Years**
(21) Appl. No.: **29/922,364**
(22) Filed: **Dec. 21, 2023**

Related U.S. Application Data

- (60) Continuation of application No. 29/771,324, filed on Feb. 22, 2021, now Pat. No. Des. 1,014,603, which is a division of application No. 29/705,673, filed on Sep. 13, 2019, now Pat. No. Des. 911,412.

(57) **CLAIM**

The ornamental design for a camera housing, as shown and described.

DESCRIPTION

FIG. 1 is a top, front and right side perspective view of a camera housing showing our new design;
FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the camera housing in which the design is embodied that form no part of the claimed design.

1 Claim, 5 Drawing Sheets
